UNITED STATES PATENT OFFICE.

ANDREW MAYER, OF PHILADELPHIA, PENNSYLVANIA.

VALVE FOR GAS-BURNERS.

Specification of Letters Patent No. 12,515, dated March 13, 1855.

To all whom it may concern:

Be it known that I, ANDREW MAYER, of the city and county of Philadelphia and State of Pennsylvania, have invented a new 5 and useful Improvement in Gas-Burners; and I do hereby declare that the following is a full, clear, and exact description of the same, reference being had to the accompanying drawings, forming a part of this specification, in which—

Figure 1 is an outside view of a gas burner, having my improvement applied. Fig. 2 is a longitudinal section of the same taken through the center. Fig. 3 is a transverse section of the same in the line x, y , of Fig. 2. Fig. 4 is a longitudinal section through the center of the regulating valve box.

Similar letters of reference indicate corresponding parts in the several figures.

This invention relates to the mode of arranging and fitting the regulating valves which are applied to gas burners to regulate the flow and consumption of the gas. 25 Owing to the minuteness and delicacy of these valves, it has always been difficult to apply them to the burner in such a way as to have their perfect operation insured, but this invention entirely overcomes this difficulty.

To enable those skilled in the art to make and use my invention, I will proceed to describe its construction and operation.

a, a , are the valves and b, b , the cups 35 which receive them, all of the usual construction. These valves and cups are commonly placed one by one, in the lower part of the burner, the cups being surrounded by white lead, to make them fit the burner 40 with perfectly tight joints. Owing to the distance the cups have to be inserted in the burner and the consequent difficulty of handling them it is almost impossible to prevent some of the white lead, getting inside the 45 cups or being so spread as to get between the valves and their seats in the cups. The valves are also likely to be clogged by the oxidation of the metal of which the burner is constructed. Instead of inserting the cups 50 and valves in the burner itself, I place them in a box or short tube c see Figs. 2, 3 and 4,

which is of suitable size to receive them. Into this tube they can be conveniently inserted as there is no difficulty in handling them, and owing to the facility for inserting 55 the cups in their proper position an extremely small quantity of white lead is necessary to make the joint around them, so little that there is no danger of its getting beyond the sides of the cup. When the cups 60 are in the tube, they are expanded to fill the tube tightly by inserting a punch in them.

The tube c , is not placed in the burner itself but in a small chamber A, which is 65 placed below the burner B and is inserted with a small quantity of white lead to keep it tight, but this white lead is in no danger of coming in contact with the valves or their seats. This chamber is made of brass or 70 some metal that is not so liable to oxidation as the metal, viz steel or iron, of which the burners are made, it is made with a male screw at the top to fit the female screw in the ordinary burner and with a female screw 75 at the bottom similar to that in the ordinary burner, and as it is customary in the trade to make all the burners with a screw of uniform size and pitch the chamber containing the regulating valves may 80 be applied to any burner in a minute by taking off the burner and screwing the chamber in its place. The chamber is made with holes in the top similarly arranged to those which cause the spread of the flame in an 85 ordinary gas burner in order to spread the gas in the lower part of the burner and prevent it blowing up through the burner in a direct stream.

What I claim as my invention and desire 90 to secure by Letters Patent, is—

Fitting the valve cups b, b , to a tube C which forms a valve box, in which all the cups and valves can be properly fitted without difficulty, and inserted conveniently in 95 their place in the burner, or into any chamber prepared to receive them, as herein fully described.

ANDREW MAYER.
